UNITED STATES PATENT OFFICE.

WILLIAM H. GANSS, OF TOLEDO, OHIO.

LOCK.

1,352,890.

Specification of Letters Patent. Patented Sept. 14, 1920.

Application filed August 11, 1917. Serial No. 185,653.

To all whom it may concern:

Be it known that I, WILLIAM H. GANSS, a citizen of the United States of America, residing at Toledo, Lucas county, Ohio, have 5 invented new and useful Locks, of which the following is a specification.

This invention relates to fastening devices, especially of the latching or locking type.

10 This invention has utility when incorporated in combination locks, as for doors and drawers of cabinets.

Referring to the drawings:

Figure 1 is a perspective view, with parts 15 broken away, showing embodiments of the invention in combination locks for desk compartments of drawer and door types;

Fig. 2 is a front elevation on an enlarged scale of the non-rotative lock elements, parts 20 being broken away;

Fig. 3 is a front elevation of the scale and index members of the lock;

Fig. 4 is a side elevation of the mounting plate and bolt retracted therein;

25 Fig. 5 is a section through the assembled lock on the line V—V, Fig. 4, but with the bolt thrown;

Fig. 6 is a perspective view, with parts 30 broken away of the mounting plate and lock;

Fig. 7 is a perspective view of the rear tumbler from the forward side thereof;

Fig. 8 is a perspective view of the forward tumbler of the lock from the rearward side thereof;

35 Fig. 9 is a perspective view of the forward tumbler of the lock from the forward side thereof, with the friction disk thereon; and

Fig. 10 is a detail view of the index members, the spindle being partially broken 40 away.

The desk or cabinet 1 may be provided with the doors 2, 3, for compartments therein, as well as drawers 4, 5, for additional cabinet compartments. The drawer 5 is

45 provided with the opening grips or handles 6, which in heavier work may be the real bolt actuating means for retraction in opening the drawer. These compartments provide mountings for combination locks in accordance with the invention herein, including an index member 7 provided with a knurled knob or head 8. After the bolt of the lock has been released, the compartment or drawer may be opened by a pull on the 50 knob 8. As the knob 8 moves outward in

response to such pull, the released bolt slides into the lock and does not interfere with this opening of the compartment or drawer. Accordingly the knob 8 does not have a bolt withdrawing action by direct connection to 60 the bolt, but the movement of the door or drawer out of the opening forces the bolt into the lock. The grips or handles 6 in opening or closing a drawer or door, indirectly cause the bolt 20 to be thrown. 65

A fixed scale or plate member 9 is mounted by pins 10 to provide centrally thereof a seat for the index member 7. Rearwardly from the member 9 is the main lock mounting plate 11 having the central sleeve 12 70 forwardly projecting concentrically of the members 7, 9. This plate 11 is mounted by the screws 13 in position on the door or drawer front inner side. This mounting plate has a second concentric forwardly 75 projecting sleeve 14 about the sleeve 12, and also an angular flange 15 having an opening 16 therethrough coacting with the bolt head 17 having the centering guide ribs 18. The upper rib 18 terminates in a projection 80 19, as is the case with the lower rib 18, which coacts with the flange 15 in limiting the outward throw of the head 17 of the bolt 20 as thrust by the yieldable means or helical spring 21 surrounding said bolt and operating 85 between the head 17 and sleeve 14.

The bolt 20, when forced toward the lock mechanism, protrudes through opening 22 in the sleeve 14. This inward travel or retraction of the bolt 20 may result from 90 movement of the drawer or door as to the cabinet, due to bevel face 23 of the bolt head 17 sliding against latch plate or casing 24 as the drawer or door is closed. Also the bolt 20 may be retracted due to the coaction 95 of bevel face 25 of the bolt head 17 sliding against latch plate 24 in opening the drawer or compartment.

The bolt 20 may be locked retracted or in withdrawn position. The member or mounting plate 11 is provided with a slot 26 (Fig. 2) in which a rectangular stem of a dog 27 provided with a protruding head 28 is mounted. With the bolt 20 retracted, say upon pushing inward by hand, the dog 27 100 may be moved to engage the upper projection 19 of the bolt. Thus the dog 27 is rendered inactive. However, in larger work the dog 27 may be operated by one on the inside of the compartment to coact with a 105 110

projection 19 to preclude bolt withdrawal and thereby check the lock against even combination opening thereof.

The combination lock comprises the rear 5 disk or tumbler 29 out of operative engagement with the sleeve 14 of the mounting plate 11. This disk 29 has its bearing about the outside of the sleeve 12. This tumbler 29 has a seat or notch 30 which in the rotation of the tumbler 29 may be brought into such registry with the opening 22 in the sleeve 14 that the bolt 20 may be retracted thereinto. On the forward side thereof, the tumbler 29 carries the projections 31, 32, 10 spaced from each other peripherally and located as may be expedient in determining combination relations for the lock.

Spaced by the loose washer 33 from the tumbler 29 is the tumbler 34 having the seat 20 or notch 35 analogous to the notch 30 of the tumbler 29, for when aligned with the notch 30 and opening 22, this notch 35 permits retraction of the bolt 20, as shown by the position of the members in Fig. 5. This second or forward tumbler 34 has centrally projecting from its forward side the cylindrical portion 36, adjacent thereto the angular keying seat 37 and the externally threaded terminus 38. From its opposite or rearward side this forward tumbler 34 has adjacent its periphery the rearwardly extending projection 39 rotatable to intercept the projections 31, 32 of the rear tumbler 29 in operating the combination lock. The angular position of the projection 39 as to the notch 35 is a matter of selection in working out the desired series of combinations. For changing or giving the lock a different combination, the index member 7 as well as the 30 scale member 9 may be shifted angularly.

A friction disk or fiber washer 42 is mounted on the cylindrical portion 36 of the tumbler 34 for clamping between the tumbler 34 and the index member 7. This clamping is yieldable. The ring 41 through its shoulder 40 tends through engagement with the seat 37 to preclude angular rotation of the ring 41 as to the tumbler 34. Nut 43 run up on threaded terminus 38 brings into action the washer 42 for a holding action sufficient for normal lock operations. This nut 43 is then locked by the similar nut 44, each being operated to position by a two prong wrench engaging the seats 45 diametrically disposed.

The index member 7 is assembled on the front tumbler 34. The spindle 46 may be inserted coaxial therewith to shield the connecting means between the tumbler and indicator and extend through the washer 33 and sleeve 12, for detachable and relatively rotatable mounting by the nut 47 concentrically of the rotative elements of the lock as well as concentrically of the sleeves 12, 14, 60 and scale member 9.

As an instance of the lock operation, it may be assumed the combination is 10—22—40. The knurled head 8 is rotated to the right to have its index point on the indicator member 7 stop at scale mark 10 of the second indicator member 9. The projection 39 of the tumbler 34 has its coaction with the projections 31, 32 of the tumbler 29 in the arc region having the notch 30. The projection 39 thus coacts with the projection 32 to carry the notch 30 past alining with the recess 22. In bringing the index member 7 back to 22, the projection in this rotation to the left engages the projection 31 and brings the tumbler 29 to have its notch 30 register with the opening 22. The third rotation of the index member 7 is now to the right from 22 to 40 to bring notch 35 in register with the opening 22 and notch 30. The drawer or door may now be opened by pulling on the knob 8 out from the cabinet, for by this action the latch plate 24 wedges the bolt head bevel 25 to slide the bolt 20 into retracted position. The lock accordingly acts as permissive of bolt throw, but does not actually throw the bolt 20.

Combination change may be simply effected without access to the lock interior. With the bolt 20 retracted, it may be so held by the dog 27 as actuated by the head 28. Then to throw the mechanism for a different combination, while the bolt 20 holds the tumblers in registry the index member 7 may be rotated to overcome the holding of the friction washer 42. If this change be from scale mark 40 to scale mark 30 then the new combination, would be in this instance 50—12—30. This setting does not disturb the operative efficiency of the washer 42, for in the tumbler manipulation the frictional holding between the tumbler 34 and index member 7 is effective.

There are few elements, simply assembled, in a device which may be cheaply produced with combination possibilities of great range, with ready re-setting advantages. Further, the device is one capable of installation in shallow walls, as one-half inch and less.

What is claimed and it is desired to secure by Letters Patent is:

1. A permutation lock comprising a tumbler having a recess, a housing having an outer sleeve surrounding the tumbler and an inner sleeve concentric with the outer sleeve providing a bearing on which the recessed tumbler is mounted, a spindle extending through the inner sleeve, said outer sleeve having an opening, a bolt movable into the opening and tumbler recess, and means mounted on the spindle for bringing the tumbler recess into registry with the outer sleeve opening to permit bolt movement thereinto.

2. A structure having an opening and an

- adjacent recess, a closure for the opening, a permutation lock having a housing carried by said closure, a bolt extending from the lock to have wedge face coaction with two sides of the structure recess, one disposed for wedging the bolt lockward as the closure is moved to closure position in the structure, and the other for moving the bolt lockward as the closure is moved from closure position, said housing having a guide limiting the bolt travel to reciprocation and rotary tumbler mechanism shiftable to preclude bolt movement lockward.
3. A lock having a tumbler provided with a lateral extension including a cylindrical portion, a keying portion and a threaded portion, an indicator member mounted on the cylindrical portion, a holding ring mounted on the keying portion, a nut on the threaded portion to maintain the tumbler, indicator member and ring assembled, a coöperating second indicator member for the indicator member mounted with the tumbler, and a bolt co-acting with the tumbler.
4. A lock having a tumbler provided with a lateral extension including a cylindrical portion and a threaded portion, an indicator member mounted on the keying portion, a friction disk disposed between the member and tumbler, a nut for clamping the member, disk and tumbler assembled, a second indicator member as to which the first indicator member is rotatable, and a bolt co-acting with the tumbler.
5. A lock having a tumbler provided with

a lateral tubular extension, a first indicator member adjustably mounted thereon, a lock housing providing a coacting second indicator member for the first indicator member, a spindle through the tumbler extension for mounting the indicators in assembled position and means for disconnecting the spindle for removal from the housing.

6. A lock comprising a housing providing a sleeve, a bearing spindle extending through said sleeve, means on the spindle assembling the spindle with the sleeve with the sleeve providing a bearing for the spindle, a tumbler mounted on the spindle independently of and axially beyond the sleeve, a second tumbler mounted on the sleeve axially from the first tumbler whereby said tumblers are mounted independently of each other, said tumblers having recesses, a bolt movable into the tumbler recesses, and means for shifting the tumblers.

7. A lock comprising a housing providing a tumbler bearing, a spindle mounted in the housing concentric with the housing tumbler bearing and providing a second tumbler bearing, axially spaced parallel tumblers mounted on said bearings, one of said tumblers having an integral extension away from the other tumbler, a relatively adjustable indicator member mounted on the tumbler extension, said housing having co-acting indicating means for the indicator member, and a bolt having its movement restricted by said tumblers.

In testimony whereof I affix my signature.
WILLIAM H. GANSS.
